ABSTRACT: A coupler-centering device includes a rack on the bottom of the coupler shank having longitudinal gear teeth so that lateral movement of the coupler causes rotation of a gear segment. The gear segment is adjustably spring mounted and is connected to a torsion rod through a hand-operated clutch. The torsion rod extends parallel to the centerline of the car immediately below the coupler shank, and its inner end is fixed to the car. Alternatively, the rod may serve as a shaft to turn a torsional rubber shear structure. The teeth of the rack are long enough to permit buff and draft movement of the coupler.

FIG. 6.

TORSIONAL RAILWAY CAR COUPLER CENTERING DEVICE

BACKGROUND OF THE INVENTION

It is necessary, particularly in long railways cars, to provide for considerable lateral movement of the coupler. For this purpose, the inner end of the coupler shank may be pivoted and springs provided for returning the coupler to its center position, as well as means for disconnecting the coupler shank from the springs to permit easy manual movement of the coupler from its center position. In such arrangements it is necessary to make the centering arrangement operable when the coupler is in different draft and buff positions. In order to meet all these requirements, coupler centering devices have become complicated. It is an object of the present invention to provide a simple, effective, compact and reliable centering device.

SUMMARY OF THE INVENTION

The invention is applied to a coupler which is swingable about a pivot at the inner end of the shank and is movable in buff and draft. A motion-converting device includes a gear rack fixed to the underside of the shank, with the teeth of the rack extending longitudinally a sufficient distance to accommodate full buff and draft movement. A gear segment is held in mesh with the rack and is connected through a hand-operated clutch to a torsion bar, the inner end of which is fixed to the car. The outer end of the torsion bar extends through the center of the gear segment to a spring-mounted support which is adjustable in height to adjust the height of the coupler. In an alternative arrangement, the gear segment is connected through the clutch to a rod coupled to a cylindrical rubber shear spring device fixed to the center sill. A swinging movement of the coupler shank turns the gear segment, and therefore places the torsion bar or the rubber shear pad under tension. The coupler is therefore urged toward its center position. If it is desired to move the coupler to an off-center position manually, for coupling to another car, the clutch is operated to disconnect the gear segment from the torsion or shear or shear pad. Thereafter, when the coupler returns to its center position during operation, the gear segment is reconnected to the torsion bar or shear device.

BRIEF DESCRIPTION OF THE DRAWING

FIG. 1 is a schematic top plan view of the coupler shank and the end of the center sill.

FIG. 2 is side view, partly in section, of the coupler centering device.

FIG. 3 is a sectional view taken along the line 3—3 of FIG. 2.

FIG. 4 is a sectional view taken along the line 4—4 of FIG. 3.

FIG. 5 is a side view, partly in section, of another embodiment of the invention.

FIG. 6 is an enlarged sectional view taken along the line 6—6 of FIG. 5.

DESCRIPTION OF THE PREFERRED EMBODIMENTS

The drawing is directed particularly to the end of the underside of a railroad car to show a coupler and the application of the invention thereto. It is obvious that similar apparatus will be provided at both ends of the car. The car has a deck 10 and a center sill 12 having a flared end 14. A coupler 16 includes a coupler head 18 and a shank 20 extending into the center sill and having pivot 22 at its inner end for permitting lateral swinging movement of the coupler. A rack 24 is fixed to the bottom of shank 20 and meshes with gear segment 26. The teeth of rack 24 are of considerable length so that segment 26 and rack 24 remain in mesh throughout the range of cushioned buff and draft movement of coupler 16. A rod or bar 28 extends through opening 30 in the gear segment 26 and into hub 31 of plate 32. Plate 32 is mounted on bracket 34

which is fixed to the underside of center sill 12. The support for plate 32 includes a pair of springs 36, 38 and a pair of bolts 40, 42 connected to plate 32 and extending through springs 36, 38 and bottom ledge 44 of bracket 34. Nuts 46, 48 are set to hold the platen bracket 34 under a desired amount of tension and at a selected height, to adjust the height at which coupler 16 is held by gear segment 26.

Gear segment 26 is coupled to rod 28 through clutch 50 including a clutch element 52 adapted to engage one face of gear 26. Clutch element 52 is slideable along a square portion 51 of rod 28. Clutch element 52 has a groove 53 which receives the ends of bail 55 of crank 54. Bail 55 is welded to cross bar 56, which is pivoted in a pair of hangers 57. Gear segment 26 has a pair of diametrically located projections 59 adapted to extend into slots 60 in clutch element 52. It is evident that the clutch will normally be engaged due to the weight of handle 58, but when the latter is lifted, the clutch will be disengaged from gear segment 26. The inner end of rod extends into sleeve 62, having a close-fitting square opening. Sleeve 62 is fixed to the underside of center sill 12 to hold the inner end of rod 28 against rotation and longitudinal movement.

When coupler 16 is connected to the coupler of another car it moves laterally as the cars travel round a curve. The movement of rack 24 turns gear segment 26, clutch 50, and end 51 of rod 28. This causes a torsional twist in the round portion 64 of the rod, so that a strong restoring force is exerted by rod 28 to recenter coupler 16. If it is desired to position coupler head 18 off-center manually for coupling to another car, handle 58 is raised. Crank 54 is then turned to pivot 56, moving bail 55 rearwardly. Clutch 50 then moves rearwardly out of engagement with projections 59 on gear segment 26. Coupler 16 can then be moved laterally without twisting rod 28. Gear segment 26 remains declutched until coupler 16 recenters; then clutch 50 is moved by the weight of handle 58 into engagement with projections 59 of gear segment 26.

The embodiment shown in FIGS. 5 and 6 utilizes the motion-converting means shown in FIGS. 1 to 4, including rack 24, gear segment 26, support and coupler height adjustment means 32—48, and clutch 50. Bar 68, however, is not a spring torsion device but serves to couple gear 26 through clutch 50 to a cylindrical shear structure 70. Shear structure 70 includes a rigid inner tube 72 and outer annular bodies 74. One or more annular shear pads 76 of an elastomeric material are bonded between tube 72 and outer bodies 74. Outer body 74 is fixed to center sill 12 by brackets 78, 80. Bar 68 is fastened to tube 72, so that rotation of bar 68 on its axis causes turning of tube 72 to place shear pads 76 under stress. Thus shear structure 70 tends to restore the coupler to its center position after a displacement. The operation of the structure of FIGS. 5 and 6 is, therefore, generally the same as that of FIGS. 1 to 4. The coupler may be cushioned in any conventional manner for buff and draft movement, and in any buff or draft position is movable laterally under the control of the recentering mechanism exercised through the gear and rack, which normally remain in mesh. When declutched, the recentering mechanism is automatically restored to operative condition only when the coupler reaches its center position.

60 We claim:

1. A centering arrangement for a railway car coupler having a shank which is movable laterally, comprising a torsion spring device having an axis of rotation parallel to the centerline of the car, said torsion device being mounted in a fixed position 65 below the coupler shank; and motion-converting means connecting the shank to said torsion device for translating lateral movement of the shank into rotation of said torsion device about said axis, said motion-converting means including a rack fixed on the underside of the coupler shank and a gear element coupled to said rack and fixed to said torsion device for rotating the same.

2. A coupler centering arrangement according to claim 1, wherein said torsion device is a torsion bar parallel to the centerline of the car having its inner end fixed to the car and its outer end connected to said gear element.

3. A coupler centering arrangement according to claim 1, wherein said torsion device includes a cylindrical rubber shear device having an axial portion fixedly connected to said gear element and an outer portion fixed to the car.

4. A coupler centering arrangement according to claim 1 including a manually operated clutch connected between said gear element and said torsion device.

5. A coupler centering arrangement according to claim 1, including means fixed to the car for supporting said gear element resiliently and adjusting the height of said gear element.

6. An arrangement according to claim 1, including a clutch connected between said gear element and said torsion device, means for manually disconnecting said clutch, and means for reconnecting said clutch automatically when the coupler is in its normal center position.

7. A coupler centering arrangement for a railway car comprising a center sill and a coupler having a coupling head and a shank which is pivotally connected to the car at its inner end for lateral swinging movement of its outer end, comprising a torsion spring device having an axis of rotation parallel to the centerline of the car, said torsion device being mounted below

the center sill parallel thereto; and motion converting means connecting the coupler shank to one side of said torsion device for translating lateral movement of the shank into rotary movement of the torsion device, said motion converting means including a gear rack in fixed relation to the shank and located on the bottom of the shank and a gear fixed to said torsion device and coupled to said rack, the teeth of the rack extending along the shank sufficient distances forwardly and rearwardly of said gear to remain coupled to said gear during draft or buff movements of the shank.

5 8. An arrangement according to claim 7, wherein said torsion device is a cylindrical rubber shear device, and a shaft extends along said axis and is fixed to said shear device and said gear to form the axes thereof.

10 9. An arrangement according to claim 7, including means for disconnecting the coupler shank from said torsion device manually and for reconnecting the coupler shank to said torsion device automatically when the coupler shank is in its center position.
